(57) **CLAIM**

I claim the ornamental design for a clip-on flexible reading light, as shown and described.

DESCRIPTION

FIG. 1 is a perspective left side view of the clip-on flexible reading light showing my new design having a flexible arm with a position adjustable light at its end;

FIG. 2 is a top view thereof;

FIG. 3 is a bottom view thereof;

FIG. 4 is a right side view thereof;

FIG. 5 is a rear view thereof;

FIG. 6 is a front view thereof;

FIG. 7 is a left side view of an alternative embodiment of the clip-on flexible reading light having a shorter flexible arm with a position adjustable light at its end;

FIG. 8 front view thereof;

FIG. 9 is a rear view thereof;

FIG. 10 is a right side view thereof;

FIG. 11 is a top view thereof; and,

FIG. 12 is a bottom view thereof.
